UNITED STATES PATENT OFFICE.

CHARLES C. BOWMAN, OF HINTON, WEST VIRGINIA.

AUTOMATIC TRAIN-STOP.

1,224,841.

Specification of Letters Patent.

Patented May 1, 1917.

Application filed May 3, 1913. Serial No. 765,233.

to all whom it may concern:

Be it known that I, CHARLES C. BOWMAN, a citizen of the United States, and a resident of Hinton, in the county of Summers and State of West Virginia, have made certain new and useful Improvements in Automatic Train-Stops, of which the following is a specification.

My present invention relates to automatic train stops, the object thereof being to provide means whereby to prevent a train from proceeding by one of the usual automatic block signals without stopping as is required by the regulations of the railroads, my invention embodying a locomotive carried mechanism and a track side mechanism, the latter being connected to the usual automatic signal and being moved to operative position by the lowering of the signal arm to danger position, and the locomotive carried mechanism being such as when actuated by the track side mechanism in operative position, it will bleed air from the train line and thus cause the brakes to be applied the same as if the engineer's brake valve were manipulated to this end.

Certain other objects which I have in mind are directed more particularly to the construction of both the locomotive carried mechanism and the track side mechanism, and comprehend the production of a durable, lasting and more particularly a practical device or apparatus which may be installed without heavy expense and which will operate without violation of any of the rules and regulations governing the operation of automatic signals and stops.

The means by which I accomplish these and certain other objects to be hereinafter clearly brought out are shown in the pending drawings forming a part of this specification, and in which—

Figure 1 is a side elevation of a railway track illustrating the track side mechanism and also showing portions of a locomotive provided with my improvements and partly broken away and in section for purposes of better illustration.

Fig. 2 is a transverse vertical sectional view through the parts shown in Fig. 1 and illustrating the connection of the track side mechanism with an ordinary form of automatic signal.

Fig. 3 is a perspective view illustrating certain portions of the track side and locomotive carried mechanisms.

Fig. 4 is a vertical section through the upper portion of the trip bar and its support taken substantially on the line 4—4 of Fig. 1.

Fig. 5 is a detail vertical section through a portion of the track side mechanism taken substantially on line 5—5 of Fig. 1.

Fig. 6 is a detail vertical section through the trip bar taken substantially on line 6—6 of Fig. 4, and

Fig. 7 is a detail section through the cut-out valve.

Referring now to these figures generally, I provide a locomotive carried mechanism which embodies certain means adapted when actuated to set the brakes, and to this end I provide a main reservoir pipe *a* which leads from the main reservoir *A* to the train line *A'* through the vertical branches *A*², standing within the locomotive cab *B* to the engineer's brake valve (not shown), the train pipe *A'* communicating with the laterally projecting branch *C* extending beneath the cab and provided adjacent its outer end with a valve *C'* of the turning plug type, the stem of which is provided with an exterior arm *c* forming a handle, and the extremity of which is provided with a stud *c'* projecting through a longitudinal slot in one end of an actuating arm *c*², the opposite end of which projects through a longitudinal slot *d* in the upper end of the vertical trip bar *D*, being secured to this trip bar by means of a transverse bolt *d'* extending through another longitudinal slot *d*² in the said upper end of the trip bar at right angles to the slot *d*. Thus by virtue of these slots, the actuating arm *c*² is flexibly connected to the trip bar *D* and is flexibly supported by means of a spring *d*³ coiled about the said upper end of the trip bar and compressed between the said actuating arm *c*² and a collar *d*⁴ secured on the trip bar below the actuating arm.

The trip bar *D* is supported so as to move vertically, in a plurality of journal pieces *e* carried by an upright beam *E* securely bolted and connected to the frame of a locomotive by means of bracket arms *E'*.

In the normal lowermost position of the trip bar *D*, the before mentioned valve *C'* is held closed, and the said trip bar is supported in this position by means of a spring *d*⁵ which is coiled therearound between its rigid collar *d*⁴ and one of the journal pieces *e*, as clearly seen in Fig. 3.

As will be seen by reference to Fig. 2,

this trip bar d is positioned so that its lower contact end terminates slightly above the level of the adjacent track rail F at a point spaced a short distance from this rail 5 upon the outside of the track, so that when it is engaged by the track side mechanism to be hereinafter described, and moved vertically, it will through the connections above described move the valve C' to open 10 position and thus bleed the train line pressure out through the end of branch pipe C to the atmosphere.

At a point normally below the upper journal piece e , the trip bar D is provided 15 with a notch d' as seen particularly in Fig. 6, said upper journal e being provided with a bracket e' from which is mounted a spring controlled pin e^2 , the inner end of which is adapted for engagement within the 20 notch d' and thus holds the trip bar in raised position. The outer end of this pin e^2 is pivotally connected intermediate the ends of an upright lever G , the upper portion of which projects through an aperture 25 in the floor of the cab B and is under control of the engineer whereby the trip bar may be released and again lowered after the train has been stopped, while the lower end of this lever is pivotally mounted upon a 30 post G' secured to and projecting laterally from the locomotive formed below the cab. The engineer is supposed to release and permit the trip bar D to lower after each actuation thereof, but may defeat the automatic 35 setting of the brakes if he so desires.

This latter function may be accomplished by the manipulation of a cut-out valve H disposed in the pipe C between the main reservoir pipe a and the before mentioned 40 valve C' , and which is normally open, the stem of this valve H having a handle h which is pivotally connected to an upright connecting rod h' the upper end of which is similarly connected to the lower angular 45 portion h^2 of a lever H' pivotally mounted in the cab B , as particularly shown in Fig. 1, and having a latch mechanism in engagement with the notched quadrant h^3 . When this valve H is closed, it may be readily seen 50 that the opening and closing of the trip valve C' will be without effect.

The track carried portion of my improvements consists of a base plate I which, as particularly shown in Fig. 3, is spiked to 55 certain of the ties at the outside of the track, and in spaced relation to the adjacent track rail F , and provided with upstanding end flanges i forming guides and adapted to receive the edges of a sliding plate J , this 60 plate being provided with laterally projecting arms j . The arms j are intermediately riveted to the plate J by rivets j' , as shown in Fig. 5, these arms having short projecting ends extending to one side of the plate 65 J toward the adjacent track rail F and

adapted to abut the same in order to limit the movement of plate J in that direction. The opposite projecting portions of arms j extend through the upstanding apertured portions i^2 of guide brackets i' projecting laterally from the base plate I , springs j^2 being coiled about the arms j and compressed between the outer side of the sliding plate J and the apertured bracket portions i^2 whereby to resist movement of side plate J in a direction away from the track rail F and to return the same to its normal position when released. 70

Secured, by means of its downwardly and inwardly bent-in portions k , to the sliding plate J , is the actuating plate K , this plate being bent and formed so that its upper surface slopes away in both directions from its central elevated portion k' . Thus with the parts in the positions as shown in Figs. 80 2, 3, and 5, and which are the normal positions, the trip bar D when passing will ride up on the actuating plate K , being given a gradual and uniform motion, and the locomotive carried mechanism will be actuated 85 through the connections before described. 90

Mounted centrally of the sliding plate J and upon the upper surface thereof, is a bracket L , having upstanding apertured portions l at its opposite end, this bracket 95 being disposed transversely with respect to the track rail and longitudinally with respect to the direction of the movement of the sliding plate. Extending through the apertured upstanding portions l is one end 100 of the connecting rod M , said end of said rod being provided with an enlarged head m between said upstanding portions and the opposite end thereof being pivotally connected to the slotted arm of a bell-crank-lever N , the other arm of which is pivotally united to the lower portion of an upright connecting arm O , the upper end of which is pivotally connected intermediate the ends 105 of the automatic signal arm of semaphore P . This is clearly shown in Fig. 2 and the bell-crank-lever N is preferably mounted in the base of an automatic signal post such as indicated at Q , the upright connecting rod O upstanding within the post whereby these 110 parts will be concealed and protected both from the weather and from tampering. 115

Thus whenever the automatic signal arm P is lowered to danger position, the parts of the track carried mechanism will be in 120 the positions indicated in the several figures and the trip bar D of a passing locomotive will be raised and the locomotive mechanism actuated as previously described. When, however, the signal arm P is raised 125 to safety position, the bell-crank-lever N will be rocked and the connecting rod M will be moved longitudinally, its head m engaging one of the upstanding bracket portions l and serving to slide the plate J and 130

the actuating plate K away from the track rail F and from the plane of movement of a locomotive carried trip bar. The particular connection between the connecting rod M and the bracket L, as before described, is such that if any of the automatic signal parts are broken or the connections between such signal and the track carried mechanism are disrupted, the sliding plate J will 10 be free to move to operative position under actuation of its spring J².

Thus from the foregoing it will be seen that I provide a mechanism, the construction of which is comparatively simple, the 15 cost of installation of which will be comparatively low, and which will be effective in operation and lasting and durable in use.

With a view to prevent the engineer from closing the cut out valve H, and negligently allowing the same to remain closed, I may 20 provide this valve with a supplemental port H⁴ in its plug h⁵ as clearly illustrated in Fig. 7, the body of the valve having a vertical port h⁶ in the outer end of which is threaded 25 the lower end of an upright pipe h⁷, this pipe extending upwardly into the cab of the locomotive as clearly illustrated in Figs. 1 and 2, and being provided at its upper end with an audible signal preferably in the 30 form of a whistle H⁸. In this manner, when the valve mentioned is shut off so as to prevent the setting of the brakes in the manner previously described, a small portion of the 35 train line pressure will constantly find its way through the port h⁴ into the pipe h⁷ and thus to the whistle, sounding this whistle

continuously until the valve H is again opened by use of the lever H', also previously described.

The pipe h⁷ is also preferably provided 40 with an intermediate stop cock h⁸ whereby when two or more locomotives are coupled and my apparatus cut out on one or more of the locomotives by closing valve H thereon, the audible signals H⁸ on these locomotives may be prevented from sounding.

I claim:

In an automatic train stop, a locomotive carried mechanism comprising the combination with the main air reservoir and train 50 pipe, of a normally closed branch pipe leading to the train pipe, a controlling valve in the branch pipe, a vertically movable trip bar journaled at one side of the locomotive and having diametrically crossing slots 55 therein, an arm projecting at one end through one of said slots, said controlling valve having an operating arm and said trip bar arm having a movable connection at its opposite end with the said controlling valve 60 arm, a clamping bolt extending through the other side of the trip bar and through the said trip bar arm whereby to secure the latter in adjusted position, a spring normally holding the trip bar in lowered position, and a manually releasable latch for holding the trip bar in elevated position.
